UNITED STATES PATENT OFFICE

GEORGE A. MACREADY, OF LOS ANGELES, CALIFORNIA

ROTARY CORE DRILL

Application filed March 14, 1929, Serial No. 346,956. Renewed October 12, 1932.

- My invention relates to rotary core drills of the double barrel type in which the "floating" inner barrel is free to rotate relative to the outer barrel.
- In this type of core drill the function of "floating" inner barrel is to move longitudinally without rotating over a core cut by rotary cutters attached to and driven by the outer barrel. In firm homogenous formation this type of core drill functions very satisfactorily but in the soft unconsolidated formations common in oilfields it does not always function so satisfactorily and cores are often broken or twisted at short intervals.
- For the purpose of orienting cores to determine the direction of stratigraphic dip in rotary drilled holes it is desirable to obtain long unbroken segments of core.
- One of the causes for difficulty in obtaining long unbroken cores of soft material is the uncertainty of knowing and maintaining the correct rate of advance of the cutters. If fed too rapidly cuttings accumulate to lock the two barrels together but if fed too slowly the cutters cut until the pipe is hanging and in most forms of core drills there is no pressure remaining to hold the floating inner barrel centered over its core with the result of a broken core.
- An object of my invention is to hold the "floating" inner core barrel on its core with uniform pressure in spite of minor variations in rate of advance of cutters, speed of cutting, or hardness of formation: and to accomplish this I make use of a compressed spring coupled in the "floating" inner core barrel member.
- With the foregoing and other objects in view which will be made manifest in the following detailed description and especially pointed out in the appended claims, reference is had to the accompanying drawing for illustrative embodiment of my invention, wherein:
- Figure 1 is a side elevation of a core drill with the middle portion of the outer barrel broken away to show the spring coupling and other novel features of my invention.
- Figure 2 is a longitudinal section of the
- spring coupling on a larger scale than Figure 1; and
- Figure 3 is a cross section at 3-3 on Figure 2.
- Similar numerals refer to similar parts throughout the several views.
- In the accompanying drawings a rotary core cutting bit designated as 1 is mounted on the lower end of the outer core barrel 2. Rotatably mounted within the outer barrel 2 is the inner core barrel member, designated in general as 3, provided with a cutting nose 4 at the lower end thereof, and a thrust bearing 5 at the upper end thereof.
- The function of the thrust bearing 5 is to transmit thrust caused by the weight of the drill pipe to the inner core barrel member 3 to force it longitudinally over a core and at the same time to reduce the rotational friction so that the rotating outer barrel 2 will not cause the inner barrel 3 to rotate. The thrust bearing 5 can be a ball bearing, a roller bearing, a point bearing, a journal bearing, or any other type of thrust bearing used in core drills. The inner core barrel member 3 includes a core receiving tube 20 provided with a core retainer not shown and a check valve 21 of any form commonly used in core drills in addition to the spring coupling designated in general as 6 which is a novel feature of this invention.
- The details of the spring coupling 6 are as follows. The coupling 7 is connected to the top of the inner core barrel member 3 preferably by screw threaded attachment to the check valve 21. Attached to coupling 7 is a shaft 8 of smaller diameter so that a shoulder 9 is formed at the joint which is preferably screw threaded. The opposite end of shaft 8 is provided with an enlargement 10 forming a shoulder 11. A sleeve 12 is mounted about the shaft 8 in such a manner as to provide a close but freely sliding fit and is provided with an end 13 facing the shoulder 9 and with an internal shoulder or end 14 to engage shoulder 11 of the shaft 8. Of course sleeve 12 is of sufficient length and accuracy to preserve the alignment of the inner core barrel member 3. Means are provided for attachment to a tube 18 within

which the enlargement 10 may slide, such as the internally threaded apron 15.

10 Optionally, relative rotation between sleeve 12 and shaft 8 can be prevented by use of a key 17 imbedded in keyways. Under some conditions relative rotation is not desirable while under other conditions it is not objectionable. Tube 18 is attached to thrust bearing 5 by threaded coupling or otherwise. Shims 19 may be provided to adjust the length of the space between end 13 and shoulder 9.

10 Shims 19 may be provided to adjust the length of the space between end 13 and shoulder 9.

A compression spring 16 is mounted about the shaft 8 between the end 13 of sleeve 12 and the shoulder 9 of coupling 7. Spring 16 can be a coil spring as shown in the drawing, a disc spring, or any other form of compression spring and the dimensions can be varied to suit the hardness of formation cored by selection of size of spring. When spring cou-

selection of size of spring. When spring coupling 6 is assembled the spring 16 may be partially compressed but not to its full limit of travel. For example: under one set of conditions using a two inch diameter core receiving barrel I used a spring made of 15 coils of half inch round rod coiled $1\frac{1}{2}$ inches inside diameter with lengths of $8\frac{1}{2}$ inches unloaded, $7\frac{1}{4}$ inches assembled in spring coupling, and $6\frac{1}{4}$ inches when compressed under full core load. These dimensions allowed the nose 4 to travel one inch longitudinally relative to bit 1.

The functions and operation are as follows. The core drill is assembled as described and lowered to the bottom of the hole preparatory to coring. When bit 1 is rotated and lowered it cuts a core and nose 4 rests on the top of the core. As bit 1 is fed deeper, weight from the drill pipe is transmitted through thrust bearing 5 to sleeve 12. If the formation is very soft spring 16 may not compress and nose 4 will then be forced into the formation and over the core causing the core to enter the core receiving barrel: and the core is prevented shearing off by the nose 4 being imbedded in the formation ahead of the bit 1. If the formation is hard spring 16 compresses allowing nose 4 to retreat behind the cutting edges of bit 1 until the pressure is sufficient to force the nose over the core: furthermore as the nose retreats behind the cutting edges of the bit the flanks of the core are relieved to permit shavings to escape laterally instead of being pushed into the rock matrix as is necessary when the nose is in soft formation ahead of the bit.

When there are changes in hardness of formation or speed of descent of bit the spring 16 adjusts the nose 4 to its proper position and holds it on the core with steady pressure. This feature contrasts with a core drill not provided with a spring when rotation is continued after ceasing to feed the rotary bit down. In the latter case the rotation of the bit soon digs hole until the bit hangs suspended instead of resting on the bottom of the

hole and the inner barrel is also suspended so that even slight vibration of the core drill may cause sufficient upward or lateral movement to break the core.

It will be understood that various changes in detail of construction may be made without departing from the spirit or scope of the invention as defined by the appended claims. 70

I claim as my invention:

1. A rotary core drill comprising an outer barrel, an inner barrel having a limited longitudinal movement relative to said outer barrel, a thrust bearing permitting relative rotation between said barrels, and a compression spring adapted to transmit thrust between said barrels, the longitudinal travel of said spring being substantially equal to the longitudinal movement between said inner and outer barrels.

2. In the inner barrel of a rotary core drill: 85
a coupling comprising a mandril threaded at
one end and provided with an enlargement
at the opposite end, a sleeve slidably disposed
about said mandril having a bore of smaller
diameter than the diameter of said enlarge- 90
ment for a portion of the length facing the
thread end of said mandril and threaded at
the opposite end for attachment in a core
barrel, a coupling threadedly connected to the
thread end of said mandril and provided 95
with threads at the opposite end for attach-
ment in a core barrel, a coil spring disposed
about said mandril between said coupling
and said sleeve, a key fitting in keyways of 100
both mandril and sleeve adapted to prevent
relative rotation therebetween, and shims
adapted to adjust the length of space oc-
cupied by said spring. 105

3. A rotary core drill comprising an outer barrel, a rotary core cutting bit on the lower end of said outer barrel, a core receiving barrel within said outer barrel having a limited longitudinal movement relative thereto and the lower end thereof adjacent said bit, a compression spring between the upper ends of said barrels having a travel substantially equal in length to the longitudinal movement between said barrels and compressible by longitudinal thrust between said barrels, and a thrust bearing adapted to transmit longitudinal thrust between said barrels and providing for relative rotation between said barrels when said spring is compressed. 105 110 115

4. A rotary core drill comprising an outer barrel, a rotary core cutting bit on the lower end of said outer barrel, a core receiving barrel within said outer barrel having a limited longitudinal movement relative thereto and the lower end thereof adjacent said bit, a compression spring between the upper ends of said barrels having a travel substantially equal in length to the longitudinal movement between said barrels and compressible by longitudinal thrust between said barrels, and a thrust bearing adapted to transmit longitudi-

dinal thrust between said barrels and providing for relative rotation between said barrels when said spring is compressed, the lower end of said inner barrel normally projecting 5 ahead of the cutting edge of said bit but retractable behind said edge by compression of said spring.

In testimony whereof I have signed my name to this specification.

10 GEORGE A. MACREADY.
